UNITED STATES PATENT OFFICE

2,421,636

TUNABLE MAGNETRON

Elmer D. McArthur, Schenectady, and Ralph J. Bondley, Scotia, N. Y., assignors to General Electric Company, a corporation of New York

Application May 29, 1944, Serial No. 537,804

8 Claims. (Cl. 315—39)

1

Our invention relates to ultra high frequency generators and it has for its object to provide a new and improved ultra high frequency generator of the electronic discharge type.

Another object of our invention is to provide a new and improved magnetron tube and circuits for use therewith.

It is a further object of our invention to provide new and improved means and method of exciting or resonating a portion of a concentric transmission line.

It is still another object of our invention to provide a new and improved magnetron tube and circuit arrangement in which the frequency of the electromagnetic waves generated therein may be adjusted over a substantial range.

Briefly stated, our invention employs a resonant cavity of the concentric transmission line type which is excited by a rotating electron field produced by the interaction of an electron discharge and a uniform magnetic field. The inner conductor of the concentric transmission line functions both as an anode for the discharge and a source of magnetic field applied perpendicular to said discharge. Means are provided for adjusting the frequency of oscillations within the cavity resonator by changing the length of the concentric transmission line without altering the continuity of the magnetic circuit of the magnetron.

The novel features which we believe to be characteristic of our invention are set forth with particularity in the appended claims. Our invention itself, together with its further objects and advantages, may best be understood by reference to the following description taken in conjunction with the accompanying drawing, in which Fig. 1 is a vertical section of a magnetron tube and circuit suitably embodying the invention and Fig. 2 is an enlarged perspective view, partly in section and partly exploded, of the magnetron tube of Fig. 1.

Referring to Figs. 1 and 2 jointly, there is shown a cavity resonator 1 of the concentric transmission line type which comprises a tubular outer conductor 2 and a centrally disposed inner conductor 3. At one end of the cavity resonator, the inner conductor 3 is maintained in coaxial relation with respect to the outer conductor 2 by means of a metallic spacing ring 4 and at its opposite end, the resonator is closed by an electron discharge device 5 which serves both to support and terminate the inner conductor 3.

The electron discharge device 5 is of the magnetron type and comprises a cathode member 6

coaxially aligned with the inner conductor 3. Concentrically surrounding the cathode 6 are a plurality of anode segments 7 (see Fig. 2) conductively connected to inner conductor 3 and forming an extension thereof and an equal number of anode segments 8 supported by and conductively connected to a metallic cup member 9 which is formed integrally with a metallic disk 10. The anode segments 7 and 8 are in interleaved spaced relation and each of the segments 7 is located diametrically across the center of cathode 6 from a corresponding anode segment 8. Moreover, the members 7, 8 are spaced apart by equal angular distances. The anode segments 7 are connected to an anode cap or connector 11 which is in screw-threaded engagement with the inner conductor 3. The segments 7, 8 are maintained in a fixed spaced relation by means of a vitreous member or envelope 12 which surrounds the anode-cathode structure and is hermetically sealed to both the anode cap 11 and the metallic disk 10. Depending from and hermetically sealed to the cup member 9 is a metallic sleeve 13, which concentrically surrounds an exhaust tube 14 which serves also as a conductive connection to the cathode 6 and one terminal of a heating element (not shown) employed therewith. A metallic cap 15 connected to tube 14 is hermetically sealed to sleeve 13 by means of an insulating tube 16. For this purpose the sleeve 13 and cap 15 preferably are formed of an iron-nickel-cobalt alloy and the seal 16 is formed of a boro-silicate glass. A lead 17 which passes through the tube 14 and is connected to the other terminal of the cathode heating element is insulated from the cap 15 by means of a glass insulating bead 18 sealed across the end of the tube after the device 5 has been evacuated. In the tube structure, the anode segments 7, 8 preferably are formed of a good conductive non-magnetic material, such as copper, while the anode connector 11, the inner conductor 3, and the metallic disk 10 are formed of iron which is plated with a good conductive material, such as copper, in order to provide a low resistance path for high frequency currents. The outer conductor 2, on the other hand, is formed of a non-magnetic material, such as copper or brass. Where the device is to operate at a single frequency, the tube envelope may enclose a choke or filter (not shown) for the cathode leads to maintain the cathode at proper potential with respect to the anode.

A magnetic field structure is provided for the cavity resonator 1 and the electric discharge

device 5 and comprises a cylindrical permanent magnet member 19 constituted of a magnetizable substance having a high coercive force and a high energy factor, for example, a magnet of the alnico type. Associated with the magnet 19 are two pole pieces 20, 21 which extend from the opposite ends of the cylindrical magnet 19 to the outer conductor 2 and are provided with cylindrical openings of a size to accommodate the outer conductor 2. The opening in pole piece 21 is provided with a shoulder 22 against which the magnetic disk 10 of device 5 abuts and is held in position by means of a threaded ring 23.

In the operation of the ultra high frequency generator thus far described, a space charge is assumed to be developed in the space between the cathode 6 and the surrounding anode structure by the application of a suitable potential impressed between the cathode lead-in tube 14 and the conductor 3 serving as an anode lead-in conductor. The electrons which compose this space charge are given a spiral or orbital motion by the uniform magnetic field which exists between the ends of the anode connector 11 and the cup member 9 serving as magnetic pole pieces to provide a magnetic field which is parallel to the axis of the device 5. Under oscillating conditions, an alternating voltage exists between the outer conductor 2, to which is conductively connected the anode segments 8, and the inner conductor 3, to which is conductively connected the anode segments 7 and, therefore, alternate sections of the composite anode structure are at any instant of opposite polarity. The anode segments 7 and 8 carry different alternating potentials to the space charge region surrounding cathode 6 and superimpose the alternating potential on the unidirectional electromagnetic field already existing between the cathode and the surrounding anode structure. Because of the interleaving of the anode segments 7, 8, any two adjacent segments are of opposite polarity for alternating currents. The presence of this alternating current field in the space charge region causes the electrons of the discharge to bunch together in groups so that the operation of the device is similar to the operation of a conventional magnetron.

Means are also provided for adjusting the frequency of the oscillations developed within the cavity resonator 1 and which comprise an adjustable annular plunger 24 provided with spring-like fingers 25, 26 contacting, respectively, the inner surface of conductor 2 and the outer surface of conductor 3. The plunger 24 preferably is formed of a magnetic material, such as iron, and the fingers 25, 26 and the surface of the plunger therebetween are provided with a good conductive coating, such as a copper plating. The plunger 24 may be moved axially to serve as an end wall for the cavity resonator 1, such movement being effected by any suitable means, such as the adjusting rod 27. The frequency of the oscillations developed within the cavity resonator 1 is determined by the length of the section of transmission line between the metal disk 10 and the plunger 24. Accordingly, the longest electromagnetic wave which can be established within the magnetron tube has a length which is equal to about four times the electrical distance between these short-circuiting members. The axial length of the pole piece 20 is adjusted to provide a desired range of wave length for the use contemplated. Energy may be abstracted from resonator 1 by any suitable output electrode means, such as the loop 28 carried by plunger 24. The

loop 28 is connected to the inner conductor of a concentric transmission line 29.

In constructing a magnetic field structure for a magnetron, it has been observed that leakage flux is kept at a minimum provided the ratio of the inner diameter of the magnet 19 to the outer diameter of the rod 3 is greater than a value of 2. Accordingly, it is contemplated in the construction of the magnetron circuits described that the inner conductor 3 be a relatively small copper-plated iron rod. In the composite magnetron structure and circuit, therefore, due to the concentric line structure of the cavity resonator, substantially no ultra high frequency electromagnetic field exists outside the cavity resonator defined by the conductors 2, 3 and, at the same time, leakage magnetic flux is kept to a minimum value.

In the foregoing description, the magnetic structure 19 has been disclosed as of the permanent magnet type. It is apparent, however, that other types of magnetic structures using energizing windings may be employed in conjunction with the particularly high frequency tube structure disclosed.

While we have shown a particular embodiment of our invention, it will of course be understood that we do not wish to be limited thereto since various modifications may be made, and we contemplate by the appended claims to cover any such modifications as fall within the true spirit and scope of our invention.

What we claim as new and desire to secure by Letters Patent of the United States is:

1. High frequency electrical apparatus comprising an electric discharge device comprising a cathode, a pair of anode segments positioned on opposite sides of said cathode, a transverse magnetic member connected to one of said segments, a longitudinal magnetic member connected to the other of said segments, dielectric means sealed between said members forming an envelope for said device, a tubular conductor conductively connected to said transverse member and concentrically surrounding said longitudinal member forming therewith a cavity resonator, and means for producing rotation of electrons emitted by said cathode comprising magnetic means surrounding said outer conductor and magnetically coupled to said members.

2. High frequency electrical apparatus comprising an electric discharge device comprising a cathode, a pair of anode segments positioned on opposite sides of said cathode, a transverse magnetic member connected to one of said segments, a longitudinal magnetic member connected to the other of said segments, dielectric means sealed between said members for forming an envelope for said device, a tubular conductor conductively connected to said transverse member and concentrically surrounding said longitudinal member forming therewith a cavity resonator, means for producing rotation of electrons emitted by said cathode comprising magnetic means surrounding said outer conductor and magnetically connected to said members, and means for adjusting the resonance frequency of said resonator including an adjustable element positioned between said members.

3. High frequency electrical apparatus comprising an electric discharge device comprising a cathode, a transverse magnetic member, a longitudinally extending magnetic member, a plurality of first anode segments conductively connected to said transverse member, a plurality of second

anode segments in spaced interleaved relation with said first segments and conductively connected to said longitudinal member, dielectric means sealed between said members constituting an envelope for said device, a tubular conductor connected to said transverse member and concentrically surrounding said longitudinal member and forming therewith a cavity resonator, and a permanent magnet concentrically surrounding said tubular member and magnetically connected between said transverse member and said longitudinal member.

4. High frequency electrical apparatus comprising an electric discharge device comprising a cathode, a transverse magnetic member, a longitudinally extending magnetic member, a plurality of first anode segments conductively connected to said transverse member, a plurality of second anode segments in spaced interleaved relation with said first segments and conductively connected to said longitudinal member, dielectric means sealed between said members constituting an envelope for said device, a tubular conductor connected to said transverse member and concentrically surrounding said longitudinal member and forming therewith a cavity resonator, a permanent magnet concentrically surrounding said tubular member and magnetically connected between said transverse member and said longitudinal member, and a movable magnetic plunger positioned between said tubular conductor and said longitudinal member for adjusting the resonance frequency of said resonator.

5. High frequency electrical apparatus comprising an electric discharge device including an even number of elongated anode elements positioned in mutually spaced generally parallel relation and providing a generally circular array, a disk-like terminal member supporting alternate ones of said elements, a second terminal member supporting the remaining anode elements, an enclosure member of generally circular cross section having one end sealed to one face of said disk-like terminal member and the opposite end sealed to said second terminal member, a cathode supported within said array of anode elements, a cavity resonator including a generally cylindrical conductor connected with said second terminal member and a larger hollow cylindrical conductor electrically connected to said disk-like terminal member.

6. An electric discharge device comprising a disk-like terminal member, a plurality of anode segments supported from said member and extending in a direction substantially perpendicular thereto, a second terminal member of smaller diameter than said disk-like terminal member, a plurality of anode segments equal in number to the segments supported by said disk-like terminal member supported from said second terminal member, a generally cylindrical enclosure means sealed at one end to said disk-like terminal member and at the opposite end to said second

terminal member to support said terminal members with the anode segments supported thereby in interleaved relation with adjacent anode segments of the resulting array connected to different terminal members, and a cathode positioned within the array of anode elements and supported from one of said terminal members in insulated relation with respect thereto.

7. High frequency electrical apparatus comprising an electric discharge device including a cathode, a plurality of anode segments positioned in generally cylindrical array around said cathode, a magnetic member positioned at one end of said array supporting selected ones of said segments, a longitudinal magnetic member positioned at the other end of said array supporting the others of said segments, means constituting a part of said device forming an hermetically sealed enclosure for said cathode and anode segments, a tubular conductor conductively connected to said first mentioned member and concentrically surrounding said longitudinal member forming therewith a cavity resonator, said members defining a magnetic path for magnetic fields directed parallel to the axis of said array and between said cathode and said anode segments.

8. High frequency electrical apparatus comprising an electric discharge device including a cathode, a plurality of anode segments positioned in generally cylindrical array around said cathode, a magnetic member positioned at one end of said array supporting selected ones of said segments, a longitudinal magnetic member positioned at the other end of said array supporting the others of said segments, means constituting a part of said device forming an hermetically sealed enclosure for said cathode and anode segments, and a tubular conductor conductively connected to said first mentioned member and concentrically surrounding said longitudinal member forming therewith a cavity resonator, said members defining a magnetic path for magnetic fields directed parallel to the axis of said array and between said cathode and said anode segments, and means for producing rotation of electrons emitted by said cathode comprising magnetic means surrounding said outer conductor and magnetically coupled to said members.
